BONING STRUCTURE FOR GARMENTS

Moe Saracheck, Allentown, Pa., assignor to Charis Corporation, New York, N. Y., a corporation of New York

Application November 1, 1934, Serial No. 751,068

2 Claims. (Cl. 2—257)

This application is filed as a continuation in part of my application Serial No. 663,619.

This invention relates to means of fastening boning in foundation garments such as corsets, 5 to prevent the boning from becoming disarranged from its original position.

Usually, the bones are so placed by the designer in garments of the kind to which the invention relates, that they extend sufficiently below the waist line to cover the fleshy parts of 10 the figure, at the same time terminating at definite points so that they will not be too long to interfere with the movements of the figure when walking, or to become uncomfortable when the 15 figure is in a sitting position. It is, therefore, of importance to the comfort of the wearer that the boning be retained in the original position intended by the designer.

Should the bones slide downwardly in the 20 pockets which are usually provided to receive them, in addition to the discomfort referred to above, the ends of the bones will not only show through the outer wearing apparel, but will in time cut through the cloth and protrude. Also, 25 the upper ends of the bones will be so far below the upper edges of the garment as to cause the cloth to wrinkle and fold over, and the garment to lose its style and fitting.

A further consideration in locating boning in 30 a garment resides in the allowance that must be made for the shrinkage of the cloth with respect to the boning. Heretofore the general method of taking care of this shrinkage has been to place the tacking across the bone pockets at a sufficient distance, usually in the neighborhood of an 35 inch from each end of the bones, to allow the cloth to shrink without shortening the length of the bone pockets to such an extent as to cause the bones to engage the ends thereof. This placing of the tacking at a distance from the ends 40 of the bones, however, has been of disadvantage, in that the bones could become displaced within the bone pockets, sometimes dropping down so as to interfere with the movements of the wearer when walking, or to become uncomfortable in a 45 sitting position. If in an attempt to thus prevent movement of the boning within the bone pockets, the tacking is placed so close to the ends of the boning as to prevent such movement, when the cloth shrinks it cannot move with reference to the boning, hence the latter becomes 50 buckled or bent, and the garment loses its shape or the bones in time cut through the cloth.

One of the principal objects of my invention is 55 to provide a construction which will overcome

the difficulties referred to above, and which will result in the boning being maintained in proper position, and at the same time allow for the shrinking of the garment with reference to the boning, without the disadvantages referred to. 5

Another object of the invention is to provide a fastening means for boning whereby, while the boning is maintained in proper position, at the same time the cloth is free to shrink with reference to the boning without inducing any binding or buckling action upon the latter. 10

A further object is to provide a fastening means for boning which will prevent the boning from dropping out of the bone pocket, even though the cloth of the latter should, through 15 wear or otherwise, be cut through so as to expose the lower end of the boning.

A further object is to provide a construction in which means for suspending the boning in the 20 pocket is provided which is adaptable to various positioning of the boning in the pocket, and to various methods of finishing the edge of the garment.

My invention comprises in general, the provision of a tape connected in suitable manner 25 with the bone at or near the upper end of the latter and forming a continuation thereof, and when embodied in a corset or the like arranged to project upwardly in the bone pocket for attachment to the garment. For convenience of 30 attachment, it is preferable, though not necessary, that the tape project out of the upper end of the bone pocket a sufficient distance so that when the binding at the upper edge of the garment is stitched in place, the stitches will run 35 across and catch the tape, thus securing the latter to the binding and the cloth of the garment and suspending the bone within the bone pocket by the tape.

In the preferred form of attachment, my invention also contemplates the stitching of the upper portion of the bone pocket at the upper 40 end of the bone, so as to prevent the latter from working upwardly.

By my construction the bone is suspended in 45 the pocket by means of the tape which is stitched in place, the cross tacking at the bottom of the bone pocket is eliminated, and hence, while the bone can move neither upwardly nor downwardly, at the same time the cloth may 50 shrink with reference to the bone without causing any binding action on the latter, and without causing any disarrangement of the lines or fit of the garment by reason of the buckling of the bone and without causing discomfiture to the 55

wearer by reason of the displacement of the bone with reference to the position originally designed for it to occupy in the garment.

I am aware that hitherto efforts have been made to suspend boning in corsets and the like from a tape attached in some way to the boning, but methods of construction hitherto attempted are not feasible for modern boning construction.

Present-day corset boning is made of flat resilient steel of the desired width and length having its surface completely water-proofed to prevent rusting of the steel from body moisture and from washing the corset. This present-day water-proofing is done with celluloid. The steel, having been cut to the desired length and its ends suitably rounded, is covered with sheet celluloid and its ends are then dipped in liquid celluloid which hardens to form thin caps.

The apparently most feasible way suggested in the prior art for attaching a tape to the boning for suspending the bone in the pocket is to puncture the steel at a suitable distance from the end and to thread through the hole thus made a tape, looping the tape upward and stitching both ends to the corset. After thoroughly testing this method of suspension, I have found that it is wholly unsuited to modern boning:

(1) The steel must be punctured after the celluloid water-proof coating has been applied. This results even under most careful operation in chipping the celluloid about the hole and thus exposing the steel where the celluloid is chipped off as well as along the cross section of the steel where the hole is made. This necessitates re-water-proofing the steel at the hole, and after rewater-proofing, reaming out or otherwise clearing the hole of accumulated water-proofing, an operation which is costly and which even with the greatest care is not uniformly successful in assuring a complete water-proofing at the hole;

(2) Puncturing the steel near its tip for the insertion of the tape weakens the steel at this point to the extent that the tip from the hole upward is liable to be broken off or bent in use.

(3) Only a small width of tape can be employed, not much wider than the diameter of the hole, for otherwise the tape wrinkles and folds at the hole and makes an objectionable bulge at this point. The use of a narrow tape results in a suspending means weak in itself and affording too small an area for stitching into the corset. Commercial manufacture of the corset practically necessitates that this stitching shall be crosswise of the tape, and with a narrow tape only a few stitches pass through the tape for suspending the boning.

(4) The edges of the hole are quite likely to be sharp and cut through the tape.

Another common suggestion of the prior art is to employ an adhesive for attaching the tape to the boning. With modern boning the choice of an adhesive becomes a matter of prime importance and thus far I have not found a suitable adhesive. But of equal importance from a commercial standpoint is the unsatisfactory and uneconomical use of any adhesive for this purpose in modern corset manufacturing production.

These difficulties in the prior art have led to extensive experimentation and testing in dealing with the various problems presented with a view of producing a structure by and in which the objects heretofore set forth may be attained. This experimenting and testing has resulted in the

completely successful structure herein set forth and claimed.

With the foregoing and other objects in view which will become more apparent as the description proceeds, reference is had to the accompanying drawing which illustrates some of the forms that the invention may take, and in which,—

Figure 1 is a front elevation of a corset bone with the suspending tape of my invention thereunto attached;

Fig. 2 is a rear elevation of the construction shown in Fig. 1 with the water-proofing of the bone broken away to illustrate its construction;

Fig. 3 is an elevational view of the construction shown in Figs. 1 and 2 embodying a modification thereof;

Fig. 4 is an elevational view of the construction shown in Figs. 1 and 2 embodied in a portion of a garment, parts being folded back for clearness of illustration, the inside of the garment being shown.

Fig. 5 is a sectional view along the line 5—5 of Fig. 4; and

Figs. 6 and 7 are views similar to Fig. 5 showing other constructions for attaching the boning to the garment.

Referring to Figs. 1 and 2, the bone 10 itself comprises a strip of spring steel 21 of desired dimensions suitably water-proofed in a manner to prevent rusting of the steel. The water-proofing illustrated is perhaps the preferred type in present-day use and comprises a sheet of celluloid 22 folded about the steel lengthwise overlapping at its edges and suitably attached to the steel. The ends of the bone are thereafter dipped in celluloid of a liquid consistency which hardens to form the caps 23, one at each end thereof.

To such a bone I attach a suspending piece of fabric of suitable weave, texture and size, such as a tape 12. This tape is substantially of the same width as the bone 10.

The attaching means, heretofore referred to as those which I have discovered to be completely satisfactory in the modern art of corset construction, consists of a band or staple 19 which is bent around the bone and the tape and clamped in position to secure the tape between the clamp and the bone as illustrated. This band should be of a size and form to project as little as possible from the bone when mounted thereon and to present to the fabric of the pocket a smooth contour, avoiding sharp edges. The band 19 further should be either water-proofed or made of a material which does not rust or corrode. What is commonly called "stainless" steel is a suitable material and when this is employed its outer edges should be rounded.

The band 19 may conveniently be clamped around the boning 10 and tape 12 immediately beneath the top cap 23 with the unbroken length of the band on the tape side of the bone, which in turn is preferably on the side of the bone on which the water-proofing material is flat and continuous. This affords a uniform frictional clamping of the tape to the bone throughout the width of each by the band 19, and I have found that in no instance has the tape been pulled away from the bone or loosened from its original position thereon in use.

The tape 12 attached as aforesaid to the bone has a long end above the band 19 of desired length, projecting upwardly from the bone on attachment to the corset, and a short end below

the band 19 of convenient length for manufacturing and of such length as to offer sufficient strength of the tape below the band to avoid unraveling or otherwise weakening the frictional joining of the tape to the bone at the band. As will be pointed out below, when the boning is placed in the bone pocket for mounting, this lower end of the tape will ordinarily be folded upwardly around the band. This is incidental to 10 convenient assembly in the art of modern corsetry, and is without function. It will be apparent, however, if desired that the lower end of the tape may be made co-extensive in length with the upper end and the two ends joined 15 when the boning is mounted in the garment.

In the modification illustrated in Fig. 3, the edges of the bone are notched as at 24 to receive the band or staple, so that the latter will not protrude to form an obstruction to the easy 20 insertion of the bone into the pocket. Furthermore, the band or staple is shown as having its ends joined on the tape side of the bone. These modifications result in a slightly smoother appearance of the outside of the garment in which 25 the boning is mounted than in the case where the preferred structure of Figs. 1 and 2 is employed.

Three variations in the mounting of the bone in the bone pocket are herein illustrated, the 30 structure of Figs. 1 and 2 being shown. Referring first to Figs. 4 and 5 of the drawing, a portion of a garment is illustrated at 5, 6 being the upper edge of the garment. The garment is illustrated as being provided with a bone pocket 35 7 which is stitched in place on the inside thereof in the usual manner, the usual lining of the pocket being indicated at 8, and the outer layer of material of the pocket being indicated at 9.

In manufacture, the bone pockets are usually 40 made separate from the garment and stitched in place on the inside of the latter during the course of manufacture, and may be designed to receive one or more bones, the pocket illustrated in the drawing being a double pocket.

Usually the pockets are stitched or tacked 45 across at a distance from the upper and lower ends of the boning, as hereinbefore referred to, such as to make a generous allowance for shrinkage.

The bone 10 with its suspending tape attached 50 as above described is inserted into its pocket at the top of the pocket and forced down into the pocket to its intended position therein, the suspending tape being preferably on the side of 55 the pocket which adjoins the fabric of the garment to act as a reinforcement in preventing the bone in use from wearing through the pocket and the fabric of the garment. Ordinarily the long end of the tape heretofore referred to will 60 then terminate flush with the upper end of the pocket and upper edge of the garment, or project thereabove and be trimmed off flush therewith. The upper edge of the garment (and pocket) is ordinarily bound with a binding material 13.

When the binding is stitched in place, the 65 stitches as at 14 not only secure the binding to the cloth of the garment and to the cloth forming the upper portion of the bone pocket, but also securely fasten the tape in position, so 70 that the bone is suspended in the pocket by the tape.

I preferably also cross-tack the pockets quite close to the upper end of the boning as at 15, to prevent any upward movement of the bones 75 with reference to the cloth of the garment. I,

however, do not cross-tack the pocket below the lower end of the boning. Accordingly no shortening of the bone pocket with reference to the boning, due to shrinkage, will cause engagement of the boning with the ends of the pocket, hence 5 there will be no binding or buckling action upon the boning which would otherwise cause it to bend or depart from its flat position against the figure when in use. Furthermore, the tendency of the boning to cut through the cloth or the 10 pocket of the garment due to shrinkage of the latter which occurs in the ordinary methods of securing the boning in position referred to above, is entirely eliminated. It will be noted that, should for any reason, either by long con- 15 tinued wear, accident or otherwise, the bone pocket, or the cloth of the garment, at the lower end of the bone be cut through, this would not cause the bone to fall out of or become dislodged from the pocket, as was the case with the old 20 method of stitching across the bottom of the pocket, but the bone will remain suspended in its original position in the pocket. It will also be noted that though the bone is normally per- 25 manently suspended within the pocket, it can be readily removed in making adjustments or alterations in the garment, by removing the stitches which secure the material of the cloth over the upper end of the bone pocket, and the cross tacking, where such is used, and thus al- 30 low the bone to be removed by drawing the tape and with it the bone, upwardly out of the pocket. This is of advantage as it is sometimes nec- 35 essary to insert shorter or longer boning than was originally designed for the garment, to ac- 35 cord with the figure of the individual wearer. The original bone having been thus withdrawn, the substituted one may readily be placed back in the pocket and the parts again replaced and 40 stitched.

In Fig. 6, I have illustrated another construction, often used on girdles where a different method of binding the top edge of the girdle is employed. In this case, the upper edge of the garment or girdle 5^a is folded over as at 20 be- 45 fore the binding tape 13^a is applied, and the upper free end of the suspending tape 12 is folded with it. The binding tape 13^a, preferably in doubled or folded condition, is then applied to the garment and the folded over edges, as illus- 50 trated in Fig. 6, being stitched adjacent its upper and lower edges through the folded over edges of the garment, the folded over end of the tape and through the bone pocket and the cloth of the garment as illustrated. In this con- 55 struction the folding over of the suspending tape and the edge portion of the garment, the placing of the binding tape upon the folded over edges of the garment as illustrated, and the ar- 60 rangement of the stitching used to secure the binding in place, provide a very secure fastening for the boning, which makes it unnecessary to use the tacking 15 across the upper portion of the bone pocket, as illustrated in Figs. 1 and 2. 65

Also, it is sometimes desirable to have the upper end of the bone disposed well below the upper edge of the garment. In such cases, the upper end of the suspending tape 12, as illus- 70 trated in Fig. 7, may not even reach as far as the binding 13 at the upper edge of the garment. The tape may still be secured to the bone pocket in position to suspend the bone therein, by means of the cross tacking 15 alone. While this construction is not as strong as the others 75

described, it is of decided advantage in manufacture, because it obviates the necessity of cutting extra long tapes for constructions in which the upper edge of the bone is to be placed 5 an unusual distance below the upper edge of the garment, and furthermore, the cross tacking 15 will, unless the garment is exposed to unusually hard usage, be sufficiently strong to adequately maintain the tape and bone in position during the life of the garment.

In all forms of the invention that have been illustrated, it will be observed that the bone is provided with a flexible, narrow strip of tape which forms an extension of the bone to project 15 upwardly in the bone pocket preferably terminating coextensive with the upper end of the bone pocket or extending therebeyond; and when embodied in the garment is stitched into place therein, preferably when the edge binding 20 is stitched into position, so that the bone in each instance is thus suspended by a flexible tape permanently attached to the garment preferably at its upper edge and/or to the bone pocket above the upper end of the bone.

25 While I am aware that it has heretofore been proposed to provide a bone pocket with a flap adapted to fold down to close the upper end of the pocket or to be raised in order to allow the removal of the bone; to secure a bone pocket in 30 position in the garment by means of lacings extending through eyelets in the garment; to stitch the bone pocket to the garment all around the perimeter of the former; also to provide the bone pocket with a slit at its upper end and 35 to provide a loop whereby the bone may be withdrawn from the pocket, none of these propositions, or any others known to me, recognize the problem of insuring the retention of the original positioning of the boning in the garment 40 in accordance with the plans of the garment without endangering the proper set and positioning of the boning, as has been accomplished by my invention, or accomplishing the other advantages accruing to my invention as set forth hereinbefore.

45 From the foregoing description of my invention it will be apparent that in its broad scope it is applicable to bones which have no covering

at all or which are covered with cloth or paper or other material not necessarily waterproof.

The foregoing description has been given for purposes of illustration of the invention, and some of the forms that it may take, but no undue limitations should be deduced therefrom, as the claims should be construed as broadly as permissible, in view of the prior art.

Having thus described my invention, what I claim as new, and desire to secure by U. S. Letters Patent is:—

1. In a boning construction for garments provided with a bone pocket, a rust-proof bone adapted for suspension in the pocket and comprising in combination a resilient member of 15 steel of suitable dimensions, waterproofing material securely applied thereto, a flexible tape having one end applied against one side only of the bone against the water-proofing material and at its other end projecting longitudinally 20 of the bone beyond the end thereof, and a rust-proof band overlying the tape and having its ends clamped around the edges of the bone and binding the tape against the bone and maintaining a frictional contact between the water-proofing and the tape such that the tape is prevented from moving longitudinally with respect to the bone when in use.

2. In a boning construction for garments, the combination with a garment having a binding 30 along the upper edge thereof and having a bone pocket, of a tape of flexible material arranged in the upper end of the said bone pocket and extending longitudinally thereto and depending below the binding, stitches securing the binding 35 to the garment and also securing said tape thereto, a smooth solid flat steel bone arranged in said pocket longitudinally thereof and freely suspended therein by said tape, said tape at its lower end lying against one side only of said bone, a band clamped around said bone and tape and securing the tape against longitudinal movement with respect to the bone, and stitching between the binding and the upper end of the bone 40 securing the sides of the bone pocket together, 45 whereby said bone is freely suspended in said pocket and adequately secured therein.

MOE SARACHEK.
